UNITED STATES PATENT OFFICE.

LEON M. HARWOOD, OF SPRINGFIELD, MASSACHUSETTS.

APPARATUS FOR CUTTING METALLIC LEAF.

Application filed December 27, 1921. Serial No. 525,240.

To all whom it may concern:

Be it known that I, LEON M. HARWOOD, a citizen of the United States, residing at Springfield, in the county of Hampden and State of Massachusetts, have invented new and useful Improvements in Apparatus for Cutting Metallic Leaf, of which the following is a specification.

This invention relates to improvements in apparatus for cutting metallic leaf, and while the invention is capable of general application it finds an advantageous use in connection with a device for depositing metallic leaf from the roll.

The main object of the invention is to provide an improved means for cutting metallic leaf, which means is quickly and conveniently operable and severs the leaf with a draw cut, accomplishing its function on the delicate leaf with accuracy and efficiency.

The invention has for another object to associate a cutting device of the character described with a device for applying or depositing metallic leaf from the roll, the arrangement being such that the supporting strip with the leaf thereon may be conveniently unwound and the amount of leaf required severed from the remainder and applied or deposited, as desired.

Other objects and advantages will appear in the following description and in the illustrative embodiment of the invention in the accompanying drawings, in which,—

Fig. 1 is a plan view of a device for applying or depositing metallic leaf and embodying my invention;

Fig. 2 is an elevational view, partly in section, thereof; and

Figs. 3 and 4 are views taken similarly to Figs. 1 and 2, respectively, showing a modification of the invention.

Referring to these drawings, the apparatus includes two spaced side plates or frames 5 which are suitably connected together near one end by a cross plate 6. Near the opposite end of each plate 5, an ear 7 is provided which is offset outwardly, the two ears serving to support between them a rod 8 suitably secured thereto. The plate 6 has fixed thereto a handle 9, by means of which the apparatus may be manually supported and manipulated.

Mounted for vertical adjustment in, and located between plates 5, is an arbor 10 which serves to support a package roll *r*

of metallic leaf and its core *c*. Such package roll consists of a continuous supporting strip *s*, such as tissue paper or the like, and metallic leaf *l* thereupon, either in continuous form or otherwise, as desired. The vertical adjustment described is, in this instance, effected by locating the end portions of arbor 10 in substantially vertical slots 11 formed in the plates 5 and springs 12, secured at one end to the arbor 10 and at the other end to plates 5, serve to draw the arbor and the package roll downwardly.

Mounted at its ends in and extending between plates 5 and adjacent the package roll *r* is a roll 13 and similarly mounted near the forward and lower corners of plates 5 is a depositing roll 14. Pivotaly mounted on a cross bar 15, mounted at its ends in plates 5, is a plate 16, having an upper facing 17 of some suitable material, such for example as celluloid, and the free end of this plate rests upon the upper portion of the periphery of roll 13. The package roll *r* is drawn against the facing 17 by the action of springs 12 and the supporting strip extends over this facing and thence to and partially around the depositing roll 14, returning over roll 13 and between the latter and the underside of plate 16. The free end of strip *s* may be pulled to unwind the leaf and, since the strip is engaged between roll 13 and plate 16, it is thereby tensioned as well as the leaf carried thereby. The facing 17 tends to electrify the leaf as it is drawn thereover and cause it to cling tightly to the supporting strip *s*.

The cross-bar 8 serves as a guide for a knife support 18 slidably mounted upon it and capable also of rocking movement thereon. To the free end of the member 18 is suitably fixed, as by the screw 19, a knife 20, herein shown as a circular knife. The important point regarding the knife is that it should have a curved portion to engage the leaf *l* and sever it with a draw cut. It is, therefore, preferably non-rotatable, but it need not necessarily be circular, as shown, although this arrangement is desirable in that, by adjustment of the knife about its axis, fresh cutting edges may be brought into play when desired. The knife 20 is intended to engage the leaf *l* while on the depositing roll 14, but it is capable of being swung upwardly in a counter-clockwise direction and then downwardly to engage and sever the leaf *l* while on the friction-

ing member 17. The knife has a travel on its guide rod 8 which is at least commensurate with the width of the leaf 7. To prevent injury to the knife, when it is moved 5 beyond the ends of the leaf, stops 21 are provided on the ears 7 to engage the member 18 and force it outwardly.

In Figs. 3 and 4, a modification of the invention is shown which is preferred where 10 the strip is to be unwound by the act of rolling the depositing roll over the article to which the leaf is to be applied. The general arrangement of this apparatus and the cutting device thereof are the same as 15 already described. In lieu of the member 16, I provide a roll 25, preferably having a peripheral covering of rubber 26, which roll is rotatably mounted in side frames 5 and so located that the package roll *r* is drawn 20 thereagainst by springs 27 acting on the ends of arbor 10. A somewhat larger depositing roll 28 is used which preferably has a peripheral covering 29 of rubber or the like, but is mounted in a similar manner 25 and location as already described. A roll 30 is supported between the rolls 25 and 28 and the strip *s* is led around roll 28 to roll 30, and over the latter to roll 25. By this arrangement, I find that the strip *s* will 30 unwind as the frame is pushed along to cause roll 28 to roll over the article to which leaf is to be applied, the roll 30 by gripping the strip between rolls 25 and 28 serving to tension the strip. The strip clings to 35 the covered roll 28 and the latter and roll 25 cause roll 30 to turn.

In operation, the leaf is unwound by pulling strip *s* or by rolling the depositing roll 40 over the article to which the leaf is to be applied, accordingly as the form shown in Figs. 2 or 4 respectively is used, the apparatus being held by the handle 9 and

manually manipulated as desired. After the desired amount of leaf has been unwound, the knife 20 is moved toward roll 45 14 to engage leaf 7 and is then drawn across the leaf to quickly and accurately seyer it. Metallic leaf is extremely delicate to handle and to cut it cleanly is not as easy of accomplishment as might be supposed. I have 50 found that the best results can be obtained under the present conditions with a non-rotary knife, which has a curved cutting edge to engage the leaf at only one point at a time, and which when drawn across 55 the leaf cuts the latter with a draw cut.

The invention has been disclosed herein in an embodiment at present preferred for illustrative purposes, but the scope of the invention is defined by the appended claims 60 rather than by the foregoing description.

What I claim is—

1. In combination, a member upon which the leaf may be positioned for cutting, a 65 slideable knife support, a non-rotary knife fixed to said support and having a curved cutting edge to engage the leaf at one point at a time, and supporting means for said member and knife support.

2. In combination, a frame, supporting 70 means thereon for a package roll of metallic leaf, a member carried by said frame over which the metallic leaf with its supporting strip is drawn as it is unwound from said roll, a slideable knife support carried by said frame, and a non-rotary knife fixed to said support and having a curved cutting edge to engage the leaf while on said member and engage the leaf at but one point at a 75 time.

In testimony whereof I have affixed my 80 signature.

LEON M. HARWOOD.
